SAND URN OR THE LIKE

George H. Hart, Chicago, Ill., assignor to Brunswick
Corporation, a corporation of Delaware

Filed Mar. 30, 1960, Ser. No. 59,945

Term of patent 14 years

(Cl. D58—18)

FIG. 1 is a side elevational view of a sand urn or the like showing my new design;

FIG. 2 is a top plan view thereof; and

FIG. 3 is a fragmentary vertical sectional view thereof, taken at about the line 3—3 of FIG. 2.

I claim:

The ornamental design for a sand urn or the like, as shown.
